UNITED STATES PATENT OFFICE.

CHARLES H. RICHARDS, OF AURORA, ILLINOIS, ASSIGNOR OF ONE-HALF TO RICHSO MANUFACTURING COMPANY, OF AURORA, ILLINOIS, A CORPORATION OF ILLINOIS.

STRUCTURAL ELEMENT FOR BUILDINGS.

Application filed March 25, 1924. Serial No. 701,718.

To all whom it may concern:

Be it known that I, CHARLES H. RICHARDS, a citizen of the United States, residing at Aurora, in the county of Kane and the State of Illinois, have invented a certain new and useful Improvement in Structural Elements for Buildings, of which the following is a full, clear, concise, and exact description.

My invention relates to building finishing boards that are made of sheet material and resides in combining therewith spacing ribs also made of sheet material to replace the furring strips of wood hitherto incorporated in buildings to preserve the proper distance between the finishing boards and the walls to which they are applied.

The spacing rib of my invention is preferably of U shape with angular and outwardly extending wings at its longitudinal edges, these wings being joined with the inner side of the board that is supplied with the improved spacing rib. The board and the base of the rib are formed with aligned screw holes which receive screws that pass through said holes and which are free of threaded engagement with said board and rib.

The invention will be more fully explained in connection with the accompanying drawing in which Fig. 1 is a view in elevation with parts broken away, illustrating the use of one embodiment of my invention; Fig. 2 is a sectional view on line 2—2 of Fig. 1; and Fig. 3 is a perspective view of a portion of the structure.

Like parts are indicated by similar characters of reference throughout the different figures.

The particular form of board illustrated is a base board 1, usually made of sheet metal, but the invention is not to be thus limited. The top edge of this board engages the plastering 2, and its bottom edge engages the floor 3. A wooden ground strip 4

is secured to the plastered wall 5, this strip 45 extending along the board midway between its top and bottom edges.

Hitherto, furring strips have been nailed to the ground strips to preserve the distance between the finishing boards and the wall. 50 In accordance with my invention, I provide a spacing rib 6 upon the inner side of the board and also made of sheet material, preferably metal. This rib is desirably formed into U shape with angular outwardly extending wings 7 at its longitudinal edges. 55 These wings are joined with the inner side of the board, as by spot welding.

The board and the base of the spacing rib are formed with aligned holes 8 and 9, at 60 suitable distances along the board and rib, to receive the fastening screws 10. The holes 9 in the base of the rib are large enough to prevent the screws from having threaded engagement with the rib, the head ends of the screws being smooth and therefore out of threaded engagement with the board.

It is obvious that changes may be made without departing from the spirit of my invention.

Having thus described my invention I claim as new and desire to secure by Letters Patent the following:

The combination with a building finishing board made of sheet material; of a spacing rib upon the inner side of said board and also made of sheet material formed substantially into U shape and joined at its longitudinal edges with said board; said board 75 and the base of said rib being formed with aligned screw receiving holes; and screws 80 passing through said holes and which are free of threaded engagement with said board and rib.

In witness whereof, I hereunto subscribe my name.

CHARLES H. RICHARDS.
